UNITED STATES PATENT OFFICE

HAROLD SLEEMAN, OF IRON RIVER, MICHIGAN

PULLEY BLOCK

Application filed May 9, 1927. Serial No. 189,926.

This invention relates to pulley blocks and, more particularly, to those which are adapted to permit the introduction of the rope or cable, or its removal, by a sidewise movement, instead of having to thread it through the block.

The objects of my invention are, first, to provide an improved pulley block having a shell comprising duplicate cheek plates which cover the sides of the pulley and are widest at their tops and have sloping or inclined edges which prevent the rope or cable from "sawing" on the edges of the pulley block and which cause the block to automatically aline itself in relation to its work, regardless of the angle at which the rope or cable leaves and enters the block by reason of the co-operation of the inclined edges with the rope; second, to provide a pulley block having relatively rotatable side plates, respectively having im-

proved cheeks which, collectively, act as spacers to prevent the sides from binding on the sheave and also as retainers for the rope or cable when in normal position but being adapted for relative turning to provide an opening through which the rope or cable may be introduced to the sheave or removed from it by a sidewise movement; third, to dispense with catches, dogs, and other mechanical elements which are liable to get out of order or to become lost or misplaced which have been used in earlier pulley blocks in order to permit sidewise introduction or removal of the rope or cable and, instead, to provide an improved construction enabling ropes to be easily

changed without requiring the use of tools of any kind; fourth, generally, to provide an improved pulley block which will always retain the rope or cable on the sheave, prevent it from "sawing" crosswise of the pulley block and to enable the pulley block to be used at any angle without possibility of the rope binding or becoming detached from the block.

In the accompanying drawings I have illustrated certain embodiments of the different improvements comprising my invention but it is to be understood that other modifications will fall within the general spirit and principle of the invention.

In the accompanying drawings:
50 Figure 1, is a side elevation of a pulley

block whose sides are fixed in relation to each other but which embodies that part of the invention where the block is widest at its top;

Fig. 2, is an end elevation thereof;

Fig. 3, is a side elevation of another form 55 of the pulley block, embodying relatively rotatable sides and a locking yoke;

Fig. 4 is an end elevation thereof, the sides being closed;

Fig. 5, is a similar view, one of the sides 60 having been turned and the yoke swung back to permit the introduction or removal of the rope;

Fig. 6, is an end elevation of another embodiment, opened for the introduction or removal of the rope, this form being provided 65 with duplicate hooks on the sides;

Fig. 7, is a side elevation of the modification shown in Fig. 6; and

Fig. 8, is a side elevation of a modification 70 of the construction embodied in Figs. 6 and 7, illustrating how the wider top of the sides and the spacers and retainers may be curved, instead of straight.

In all of the embodiments of the invention 75 which are illustrated, the sides 1 and 2 substantially cover the pulley, are widest at their tops, where the hook that is used to anchor the pulley block is located, and have sloping edges which insure the return of the rope or cable 80 to the pulley should the rope tend to divert from the plane of the pulley block, and prevent the rope from "sawing" on the pulley block.

The purpose of this construction is to cause 85 the pulley block to automatically aline itself with its cable or rope and its work regardless of the angle at which the rope leaves and enters the block.

In Figs. 1 and 2, the sides 1 and 2 are rigidly connected by the top 3 but in all of the other forms of the invention which are illustrated, the sides 1 and 2 are relatively rotatable.

Suitably swivelled in the top 3 is a hook 95 4 by which the pulley block is anchored whenever it may be required for use. The pin 5 on which the pulley or sheave 6 is rotatably mounted, is provided with a cotter 7 to prevent its detachment and it has a headed pin 8 100

passing therethrough whose head 9 engages the side 2 for the purpose of preventing the pin 5 from rotating.

In the form shown in Figs. 3 and 4 the sides 1 and 2 are separate and are relatively rotatably mounted on the pin 5. Either one of the sides may be turned, as illustrated in Fig. 5, when it is desired to change the rope. The sides 1 and 2 have metal straps 10 suitably riveted or secured thereto which are provided 10 at their outer ends with eyes 11.

A yoke 12 to which the hook 4 is swivelled, has eyes 13, and there are pins 14 which pass through the eyes 11 and 13 to lock the sides 15 1 and 2 in position. The pins 14 may have any suitable retainers 15 to prevent them from becoming detached.

An additional feature of my invention resides in combined spacers and cheeks 16 extending across the sides 1 and 2 and, collectively, serving as retainers for the rope, as shown in Fig. 4. Collectively, these spacers and retainers 16 overhang the sheave 6 and prevent the rope from binding or becoming detached from the sheave. When one of the sides is swung around and the yoke 12 is thrown back as shown in Fig. 5, a space 17 is provided through which the rope may be passed in a sidewise direction either to insert 30 it in the pulley block or to remove it, thus obviating the necessity of threading the rope through the block.

The curved inner surfaces 18 of the retainers 16 prevent any chafing on the rope.

35 The parts 16 may be integral with the sides 1 and 2 as shown in Figs. 3, 4, and 5, or they may be separately constructed and suitably attached to said sides by rivets 19 or other fastenings as illustrated in Fig. 6.

40 The retainers 16 also serve as spacers as they will, by their contact, prevent the sides 1 and 2 from pressing against and binding on the sides of the sheaves 6.

In order to open the pulley block it is only 45 necessary to withdraw one of the pins 4 and to swing back the yoke 12 and rotate the side 1.

In the construction shown in Figs. 6 and 7, the yoke 12 and the pins 14 and straps 12 are 50 dispensed with and each of the sides 1 and 2 is provided with a hook 4^a which, collectively, 55 constitute a double hook when the sides 1 and 2 are in their normal position. It is not necessary, to provide in this construction, any means for locking the sides together because the hooks are both anchored, in side by side arrangement, when the block is closed and is in use. The hooks 4^a are preferably carried by 60 straps which are suitably secured, as by rivets 20 to the sides 1 and 2. The sides 1 and 2 are provided with combined rope retainers and spacers 16 extending across the wider tops thereof, as with the construction shown in 65 Figs. 3, 4, and 5 and these combined retain-

ers and spacers serve the same purpose as previously described.

In the construction shown in Figs. 6 and 7 there is no pin to remove or replace, but all that is required to open the block is to detach the hooks from their anchorage and swing back either of the sides into the reversed position shown in Figs. 6 and 7, whereupon the rope may be changed. When the rope is again in position, the sides are swung 75 around to bring them into alignment and the hooks are then side by side so that the pulley may be anchored and used.

In Fig. 8 I have illustrated how the tops of the sides 1 and 2 may be curved and the 80 combined retainers and spacers may be curved, instead of straight, as in Figs. 3 to 7 inclusive.

The combined retainers and spacers 16 should, preferably, extend clear across the 85 sides 1 and 2 from one edge to the opposite edge thereof.

What I claim is:

1. A pulley block comprising a pulley, relatively rotatable sides substantially covering the sides of the pulley and which are provided on their inner walls with combined rope retainers and side spacers adapted, collectively, to overhang the pulley, said sides being widest at their tops and having the aforesaid retainers and spacers extending substantially across said sides at their widest tops to prevent the rope from "sawing" laterally across the pulley, and hook means carried by the widest tops of the sides for anchoring the pulley block and for keeping the sides in alignment with the rope retainers and spacers facing each other for the purpose of collectively overhanging the pulley.

2. A pulley block comprising a pulley, a bearing pin on which said pulley is mounted, side plates through which the pin passes and which are located on opposite sides of the pulley, said side plates being widest at their tops and mounted on said pin for alignment or relative turning, combined rope retainers and spacers extending across the wider tops of the side plates and adapted to face each other and overhang the pulley when the side plates are in closed position, hook means being provided for the side plates to hold them in closed position and to anchor the pulley block, and a headed pin attached to the bearing pin and serving as a means for securing one of the side plates to the bearing pin to prevent the bearing pin from turning.

In testimony whereof I affix my signature.
HAROLD SLEEMAN.
